SASH AND STORE FRONT CONSTRUCTION

Clyde D. Lowry, Toledo, Ohio, assignor to Libbey-Owens-Ford Glass Company, Toledo, Ohio, a corporation of Ohio

Application August 20, 1937, Serial No. 160,062

10 Claims. (Cl. 20—56.4)

The present invention relates to improvements in sash and store front constructions.

Generally speaking, this invention has to do with an improved type of construction for supporting and holding lights of glass in glazed openings, for example, in windows, store fronts, and the like. The usual type of sash and store front construction ordinarily comprises a stationary back section and a movable front section associated with one another in a manner to clamp the light of glass in place therebetween. The back section is usually supported on a wooden sill and secured to a wooden back stop carried by said sill. Heretofore, considerable difficulty has been encountered with this type of construction in that there is a tendency for water and moisture to seep in between the metal sash construction and wooden sill causing dry rot and resulting in a relatively rapid aging and deterioration of said wooden sill and wooden back stop, as well as causing warpage of said sill and back stop, which tends to throw the metal sash construction out of alignment.

The primary object of the invention resides in the provision of a metal sash and store front construction which will effectively prevent the seepage of water and moisture between said construction and the wooden sill and back stop with which it is associated, thereby maintaining the said sill and back stop perfectly dry and eliminating dry rot, deterioration, and warpage, as well as reducing to a minimum the necessity of repair or replacement of the said sill and back stop.

Other objects and advantages of the invention will become more apparent during the course of the following description, when taken in connection with the accompanying drawings.

In the drawings, wherein like numerals are employed to designate like parts throughout the same:

Fig. 1 is a front elevation illustrating a store front embodying the present invention;

Fig. 2 is a vertical sectional view through one form of metal sash construction embodying the invention;

Fig. 3 is a perspective sectional view of portions of the back and front sections of the sash construction before being assembled;

Fig. 4 is a sectional view illustrating the application of the invention to the top of a window opening, and

Fig. 5 is a vertical sectional view showing another form of sash construction embodying the invention.

With reference first to Fig. 1, the numeral 10 designates in its entirety a glazed opening in which is mounted a sheet of glass 11 supported in the window opening by the metal sash construction 12 arranged at the top, bottom, and sides of said window. As shown, the building is faced with stone, Vitrolite, or other ornamental slabs or panels 13. The metal sash construction 12 embodying the invention may take a variety of different forms; two different types of constructions being illustrated in Figs. 2 and 5 by way of example.

Referring to that form of the invention illustrated in Figs. 2 and 3, the metal sash construction 12 is mounted on a wooden sill 14 and is secured to a wooden back stop 15 which is carried upon said sill. The wooden sill 14 may be faced with Vitrolite or other decorative sheeting 16, being held in position by a mastic 17 or other suitable supporting means.

The sash construction 12 comprises a stationary back section 18 and a movable front section 19 associated with one another to clamp the glass sheet 20 in position therebetween. The back section 18 comprises a vertical rear wall 21 which abuts the wooden back stop 15 and is secured thereto by wood screws 22. Formed integral with the rear wall 21 adjacent its upper end is an inwardly directed gutter portion 23 terminating in a substantially vertical lip 24 engaging the inner face of the glass sheet 20.

Formed integral with the rear wall 21, at the lower end thereof, is a forwardly directed substantially horizontal ledge 25, having at its outer end a vertically thickened portion or web 26 from which extends a horizontal base plate 27. The front end of the base plate 27 is provided with a raised forwardly extending flange 28 which cooperates with the outer end of said base plate to form a substantially U-shaped channel 29 receiving the lower end 30 of the front section 19.

The front section 19 comprises a face member 31 provided at its upper end with a lip 32 engaging the outer face of the glass sheet 20, said sheet being supported at its lower edge upon a plurality of setting blocks which, while not shown, are well known in the art. Carried by the face piece 31 are a plurality of spring arms 33 secured at their upper ends in a groove 34 formed in said face piece, while carried at the lower end of each spring arm is a lever member 35 comprising a head 36 from which extends a substantially horizontal lever arm 37. The head 36 is provided with a series of teeth 38 adapted for selective engagement with the tooth or rack portions 39.

formed on the upper surface of the base plate 27. The tensioning or adjusting means comprises a plurality of set screws 40 threaded through the gutter portion 23 of the back section 18 and adapted to engage the outer ends of the lever arms 37.

To install a light of glass in an opening to be glazed, the back section 18 is first properly secured in place by the screws 22, after which setting blocks are arranged upon the base plate 27 of said back section to support the lower edge of the glass sheet 20. These blocks may be arranged at spaced intervals and should be of a construction adequate to carry the load of the glass without danger of the glass chipping by reason of contact therewith.

The front section 19, equipped with the desired number of spring arms 33 and lever members 35, is then moved into position by placing the end 20 30 of the face piece 31 under the flange 28 and shoving the same toward the rear section 18 to bring the lip 32 into contact with the outer face of the glass sheet 20, and the inner face of said sheet into contact with the lip 24 of the back section. When properly positioned in this way, the teeth 38 of the lever members 35 will engage a portion of the toothed rack 39 and during this installation, the tensioning screws 40 are all in retracted position so that they will not interfere 30 with proper assembling of the parts. To then secure the glass sheet 20 and front section 19 in position, the tensioning screws 40 are tightened down to the maximum limit possible. This limit will be determined by engagement of the lever arms 37 with the ledge 25, said ledge acting as a positive stop to prevent excessive tensioning of the screws and thereby prevent excessive pressure from being applied to the glass sheet which might result in the breakage thereof. During the 40 tightening of the screws 40, the lever arms 37 will be forced downwardly so that they will rock about the toothed portion 39 on the base plate 27 and as the teeth 38 are in engagement with said toothed portion, movement of the lever arms 45 results in a rocking motion which in turn bends or flexes the spring arms 33. It is this spring tension which clamps the glass sheet 20 between the front and back sections.

When in relaxed position, the spring arms 33 50 are in a substantially vertical plane, as shown in Fig. 2, so that as the springs are flexed by movement of the levers 37, the pressure exerted upon the glass is in a direct longitudinal or horizontal plane regardless of the thickness of the glass 55 being installed. All of the tensioning screws 40 are operated to bring the levers 37 into contact with the ledge 25 which eliminates any danger of excessive pressure being exerted upon the glass and the necessity for judgment on the 60 part of the operator.

As brought out above, it is the aim of this invention to prevent water and moisture from seeping in between the back section 18 and wooden sill and back stop, whereby to protect the said sill and back stop against deterioration and warpage as well as reduce to a minimum the necessity for repair and replacement of these parts. To this end, there is provided a metal sill member or cover plate 41 which rests upon the 65 wooden sill 14 and which in turn supports the base plate 27 of the back section. The sill plate 41 is provided at its forward end with a down-turned flange 42 which overlaps the front edge of the wooden sill and covers the marginal portion of the ornamental facing 16 to give a proper

finished effect. The rear end of the sill plate abuts the wooden back stop 15 and is provided with a forwardly directed wedge portion or element 43 spaced above said sill plate and connected thereto by a web 44, said wedge portion 5 55 cooperating with the sill plate to form a horizontal groove or channel 45.

Formed integral with the back section 18 is a rearwardly extending wedge portion or element 46 which is received within the channel 45 for 10 the sill plate. The wedge portion 46 in turn cooperates with the ledge 25 to provide a horizontal channel or groove 47 within which the wedge portion 43 on said sill plate is received. The channels 45 and 47 face in opposite directions to 15 receive the wedge portions 43 and 46 which are arranged in overlapping, interlocking engagement with one another. Thus, the upper face of the wedge portion 43 is substantially horizontal and this is also true of the lower face of the 20 wedge portion 46, which is in horizontal alignment with the base plate 27. The inner meeting faces 49 and 50 of the wedge portions 43 and 46 respectively are, however, correspondingly beveled so as to provide a sliding, wedging action 25 therebetween.

In the installation of the sash construction, the sill plate 41 is first mounted upon the wooden sill 14, after which the back section 18 is placed upon the sill plate and secured to the back stop 30 15 by the screws 22. When this is done, the back section is forced rearwardly so that the wedge portion 43 of the sill member will be received in the channel 47, while the wedge portion 46 is received in the channel 45. As the 35 screws 22 are tightened, the beveled surfaces 49 and 50 of the wedge portions 43 and 46 respectively will slide over one another with a definite wedging action and form a water-tight joint which will effectively prevent the passage of 40 water and moisture therebetween. The length of the wedge portions 43 and 46 is slightly less than the depth of the channels 45 and 47 so that when the back section is secured in place, the outer ends of said wedge portions will terminate 45 slightly inwardly of the bottoms of the channels as shown in Fig. 2. These spaces at the bottoms of the channels 45 and 47 act as capillary breaks to prevent the passage of water or moisture. With this construction, water and moisture is 50 effectively prevented from passing between the wedge portions 43 and 46 and finding its way between the sill plate and wooden sill, and likewise between the back section and wooden back stop.

In order to assist in preventing water and 55 moisture from seeping in beneath the base plate 27, the said plate may be provided with one or more longitudinally extending grooves 51 in which is disposed suitable calking material 52. The grooves 51 will also act as capillary breaks 60 if no calking material is used.

As shown in Fig. 1, the metal sash construction 12 is adapted to be used around the entire opening 10 to be glazed and in Fig. 4, the sash construction above described is shown as applied to 65 the top of the window opening. In this case, however, the head plate 53 covering the wooden top or lintel 54 of the window is of a slightly different construction than the sill plate 41 in Fig. 2. Thus, the head plate 53 extends at its 70 forward end beyond the lintel 54 and is provided with a vertical flange 55 overlapping the marginal portion of the ornamental facing 56 and secured in place by mastic 57 or other suitable supporting means. Formed integral with the 75

flange 55 and spaced above the bottom of the lintel 54 is an inwardly directed horizontal ledge 58 for supporting the ornamental facing 56 and terminating in a vertical leg 59 which is secured 5 to said lintel by wood screws 60. With this construction, any water or moisture which may pass downwardly between the flange 55 and ornamental facing 56 will be prevented by the vertical leg 59 from coming into contact with the wooden 10 lintel 54. If desired, the lower portion of the flange 55 can be spaced from the ornamental facing 56 to provide a recess 61 for catching any water or moisture which may pass downwardly between said flange and ornamental facing.

15 In Fig. 5 is disclosed another form of sash construction embodying the present invention and wherein the wooden sill is also designated 14 and the wooden back stop 15, said sill being faced with Vitrolite or other ornamental slabs or 20 panels 16 secured in place by mastic or the like.

17 The wooden sill 14 is covered by a metal sill plate 62 provided at its forward end with a down-turned flange 63 overlapping the upper end of the ornamental facing 16, while provided 25 at the rear end of said sill plate is a forwardly directed wedge portion 64 similar to the wedge portion 43 in Fig. 2. The metal sash construction comprises stationary back section 65 and movable front section 66 provided with lips 67 30 and 68 respectively between which the glass sheet 69 is adapted to be secured. The back section 65 is provided with a vertical rear wall 70 which abuts the wooden back stop 15, said rear wall being provided at its lower end with a forwardly 35 directed horizontal ledge 71 and a forwardly directed horizontal base plate 72 connected with said ledge by a web 73. Also formed integral with the web 73 is a forwardly directed flange 74 co-operating with the base portion 72 to provide a 40 channel within which the in-turned flange 75 of the front section 66 is received, said front section comprising a face plate 76 formed at its upper end with said glass engaging lip 68 and at its lower end with said in-turned flange 75. The 45 face plate 76 is secured in position by screws 77 which pass beneath the glass sheet and through openings in the rear wall 70, being screwed into the back stop 15.

Also formed integral with the web 73 and extending rearwardly is a wedge portion 78 similar to the wedge portion 46 in Fig. 2, said wedge portion 78 being received beneath and co-operating with the wedge portion 64 to form a water-tight joint, the inner surfaces of said wedge portions being correspondingly beveled as at 79. The base plate 72 may also be provided, if desired, with one or more grooves filled with calking material 80, while the glass sheet 69 can be supported at its lower edge upon a plurality of spaced setting blocks 81.

60 It is to be understood that the form of the invention herewith shown and described is to be taken as the preferred embodiment of the same, and that various changes in the shape, size and 65 arrangement of parts may be resorted to without departing from the spirit of the invention or the scope of the subjoined claims.

I claim:

1. In a sash or store front construction, the 70 combination of a fixed section and a movable section adapted to receive and grip a pane of glass therebetween, means for securing said movable section in clamping relation to said fixed section, a sill plate extending rearwardly entirely beneath the fixed section and upon which said 75

fixed section is mounted, and wedge portions carried by said sill plate and fixed section at the rear ends thereof and interlocking one another to form a water-tight joint, the rear end of said sill plate being substantially flush with the rear end of said fixed section. 5

2. In a sash or store front construction, the combination of a fixed section and movable section adapted to receive and grip a pane of glass therebetween, means for securing said movable section in clamping relation to said fixed section, a sill plate extending rearwardly entirely beneath the fixed section and upon which said fixed section is mounted, and oppositely extending wedge portions carried by said sill plate and fixed section at the rear ends thereof overlapping and interlocking one another to form a water-tight joint, the rear end of said sill plate being substantially flush with the rear end of said fixed section. 10 15 20

3. In a sash or store front construction, the combination of a fixed section and a movable section adapted to receive and grip a pane of glass therebetween, means for securing said movable section in clamping relation to said fixed section, a sill plate extending rearwardly entirely beneath the fixed section and upon which said fixed section is mounted, said sill plate having a channel formed therein at its rear end, and a wedge portion carried by said fixed sections at 25 30 the rear thereof and fitting in said channel to provide a water-tight joint, the rear end of said sill plate being substantially flush with the rear end of said fixed section.

4. In a sash or store front construction, the 35 combination of a fixed section and a movable section adapted to receive and grip a pane of glass therebetween, means for securing said movable section in clamping relation to said fixed section, a sill plate extending rearwardly entirely 40 beneath the fixed section and upon which said fixed section is mounted, said fixed section having a channel formed therein at the rear end thereof, and a wedge portion carried at the rear end of said sill plate and fitting in said channel to 45 provide a water-tight joint, the rear end of said sill plate being substantially flush with the rear end of said fixed section.

5. In a sash or store front construction, the combination of a fixed section and a movable 50 section adapted to receive and grip a pane of glass therebetween, means for securing said movable section in clamping relation to said fixed section, a sill plate extending rearwardly entirely 55 beneath the fixed section and upon which said fixed section is mounted, said sill plate and fixed section being provided at the rear ends thereof with channels opening in opposite directions, and wedge portions carried by said sill plate and back section and fitting in said channels to provide a water-tight joint, the rear end 60 of said sill plate being substantially flush with the rear end of said fixed section.

6. In a sash or store front construction, the combination of a fixed section and a movable 65 section adapted to receive and grip a pane of glass therebetween, means for securing said movable section in clamping relation to said fixed section, a sill plate extending rearwardly entirely 70 beneath the fixed section and upon which said fixed section is mounted, said sill plate and fixed section having oppositely directed, substantially horizontal wedge portions at the rear ends thereof engaging one another in overlapping relation to provide a water-tight joint, the rear end of 75

said sill plate being substantially flush with the rear end of said fixed section.

7. In a sash or store front construction, the combination of a fixed section and a movable section adapted to receive and grip a pane of glass therebetween, means for securing said movable section in clamping relation to said fixed section, a sill plate extending rearwardly entirely beneath the fixed section and upon which said fixed section is mounted, said sill plate and fixed section having oppositely directed, substantially horizontal wedge portions at the rear ends thereof of engaging one another in overlapping relation to provide a water-tight joint, the contacting faces of said wedge portions being correspondingly beveled and the rear end of said sill plate being substantially flush with the rear end of said fixed section.

8. In a sash or store front construction, the combination of a fixed section and a movable section adapted to receive and grip a pane of glass therebetween, means for securing said movable section in clamping relation to said fixed section, a sill plate extending rearwardly entirely beneath the fixed section and upon which said fixed section is mounted, said sill plate and fixed section being provided at the rear ends thereof with channels opening in opposite directions, and wedge portions carried by said sill plate and back section and fitting in said channels to provide a water-tight joint, the outer ends of said wedge portions being spaced from the bottoms of said channels to provide a capillary break and the rear end of said sill plate being substantially flush with the rear end of said fixed section.

9. In a sash or store front construction, the combination of a fixed section and a movable section adapted to receive and grip a pane of

glass therebetween, means for securing said movable section in clamping relation to said fixed section, said fixed section having a substantially vertical rear wall provided adjacent its lower end with a forwardly directed channel, and a sill plate extending rearwardly entirely beneath the fixed section and upon which said fixed section is mounted, said sill plate being provided at its rear end with a forwardly directed wedge portion received in the channel in said fixed section, the rear end of said sill plate being substantially flush with the vertical rear wall of said fixed section.

10. In a sash or store front construction, the combination of a fixed section and a movable section adapted to receive and grip a pane of glass therebetween, means for securing said movable section in clamping relation to said fixed section, said fixed section having a substantially vertical rear wall provided adjacent its lower end with a forwardly directed ledge having a depending web at the front end thereof and from which extends a rearwardly directed wedge portion cooperating with said ledge to form a forwardly directed channel in the said rear wall of said fixed section, and a sill plate extending rearwardly entirely beneath the fixed section and upon which said fixed section is mounted, said sill plate being provided at its rear end with a forwardly directed wedge portion which is received within said forwardly directed channel in the fixed section and in contact with said wedge portion carried by the said fixed section, the rear end of said sill plate being substantially flush with the vertical rear wall of said fixed section.

CLYDE D. LOWRY.
